(57) **CLAIM**

The ornamental design for a brake line bleeding device, as shown and described.

DESCRIPTION

FIG. 1 is a perspective view of my new design for a brake line bleeding device.

FIG. 2 is an elevational view from one side of my new design. An elevational view of the opposite side would be a mirror image thereof.

FIG. 3 is an elevational front view of my new design.

FIG. 4 is an elevational rear view of my new design.

FIG. 5 is a top plan view of my new design; and,

FIG. 6 is a bottom plan view of my new design.
